UNITED STATES PATENT OFFICE.

GEORGE F. HULLINGS AND DAVID P. MOORE, OF WASHINGTON, DISTRICT OF COLUMBIA.

STAPLE-AFFIXING MACHINE.

1,117,673.

Specification of Letters Patent. Patented Nov. 17, 1914.

Application filed April 27, 1914. Serial No. 834,746.

To all whom it may concern:

Be it known that we, GEORGE F. HULLINGS and DAVID P. MOORE, citizens of the United States, residing in the city of Washington and District of Columbia, have invented certain new and useful Improvements in Staple-Affixing Machines, of which the following is a specification, reference being had therein to the accompanying drawing.

Our invention relates to improvements in staple affixing machines, one object of the present invention being the provision of a peculiar anvil mounting whereby the machine is adapted for various kinds of work, as stapling corners of boxes, telescopic boxes, fold flap closure boxes, and papers, there being provided means for quickly adjusting and locking the anvil in any selected position.

A further object of the invention is to provide a staple affixing machine, in which the magazine and plunger are quickly detachable from the base and operating mechanism so that the same may be readily removed and replaced when the occasion may arise.

A still further object of the invention is to provide in addition to the stapling means, perforating devices that produce perforations in the paper or box about the staple, whereby the smaller piece of material surrounded by the perforation may be removed from the box to permit access to the interior thereof without destroying the complete box.

A still further object of the present invention is to so combine a pivoted staple carrying magazine having a spring elevated plunger, and a spring elevated main operating lever, depressible through a treadle, that when the treadle is depressed, the lever in moving downwardly will through the plunger and the resistance of the spring of the plunger depress the magazine upon the anvil, the plunger not being affected in its downward movement until the magazine is at rest.

With the foregoing and other objects in view which will appear as the description proceeds, the invention resides in the combination and arrangement of parts and in the details of construction hereinafter described and claimed, it being understood that changes in the precise embodiment of

the invention herein disclosed can be made within the scope of what is claimed without departing from the spirit of the invention.

In the drawings—Figure 1 is a side elevation of the complete machine assembled for use. Fig. 2 is a side elevation of the operating parts of the machine on an enlarged scale. Fig. 3 is a top plan view of the anvil, and the adjacent portion of the base. Fig. 4 is a bottom plan view of the anvil, the operating and pivot members being in section. Fig. 5 is a bottom plan view of the base and anvil as viewed in Fig. 4. Fig. 6 is a section on line 6—6 of Fig. 3. Fig. 7 is a top plan view of a modified form of anvil. Fig. 8 is a bottom plan view of the magazine adjacent the plunger end. Fig. 9 is a detail view of the operating rods and clamps.

Referring to the drawings, the numeral 1 designates a bracket, which is adapted to be fastened to one side or corner of a table or suitable support 2, so that the base 3 and the auxiliary base 3' of the machine is properly disposed beyond the top of the table for ready operation upon different classes of work.

Upstanding from the base 3 at the rear end thereof is a supporting member or standard 4 which has disposed in the upper end 85 thereof, a pivoting pin 5 for the main operating lever 6. This operating lever 6 has insertible intermediate of its ends, an apertured pin 7 which has threaded through the opposite ends thereof, the two parallel operating rods 8 which extend downwardly and are projected through the clamping bar 9 and secured adjustably thereto by means of the set screws 10. A set screw 11 secures the single rod 12 in proper relation so that the foot treadle 13 will be properly elevated above the floor for manipulating to draw the lever 6 downwardly, as will presently appear.

Carried by the supporting member 4 and projecting forwardly therefrom, is a lug 14 provided with a spring holding pin 15 which receives the lower terminal of the coiled spring 16, while the other terminal engages the pin 17 disposed upon the under side of the main operating lever 6. This spring has a normal tendency to expand and therefore elevates the lever 6 to hold it in the normal position as shown in Fig. 2. Carried by the auxiliary base 3' adjacent the 110

rear end thereof is an apertured lug 18 which has mounted therein by means of the removable pin 19, the staple magazine 20. This magazine is disposed so that its forward end is moved to and from the forward end of the auxiliary base 3', the purpose of which will presently appear.

Mounted for sliding movement in the free end of the magazine 20 is a plunger 21 which is normally held elevated by means of the coiled spring 22, a removable pin 23 being projected through the upper end thereof and the elongated slot 24 of the main operating lever 6, so that when the lever 6 is primarily moved downwardly the spring 22 will offer sufficient resistance to permit the magazine 20 to be placed so that its lower edge is in parallel with the upper surface of the base 3 before the plunger 21 is depressed to sever and drive a staple S from its strip. Thus there is a successive action between the lever 6, the magazine 20, and the plunger 21, the springs 16 and 22 coöperating in the movements of these parts to and from the anvil 25.

The anvil 25 has projected therethrough its pivoting pin 26, which is disposed within the auxiliary base as clearly illustrated in Fig. 6 and is held against upward displacement by means of the locking screw 27. Projected through the arcuate slot 28 formed through the base and auxiliary base with the center of the pin 26 the center of the slot, is a screw 29 which is threaded in the anvil 25 so that when the milled head 30 is manipulated, the portion 31 thereof will be moved into and out of engagement with the under side of the base 3, so as to clamp the anvil 25 and release the same from adjusted position. The block 25 due to the arcuate slot 28 which is one-quarter of a circle is thus permitted a movement of 90 degrees, the purpose of which will presently appear.

Seated within the upper surface of the block 25 and removably attached thereto by means of the screws 32' is a hard tempered plate 32 which is provided with the blade anvil 33 carrying the clenching recess 34 and the narrower blade anvil 35 which is provided with the clenching recess 36. By this means it will be seen that either one of the anvils may be positioned so that its clenching recess is disposed below the plunger 21 to receive and clench the staple which is detached and driven by the plunger.

As clearly illustrated in Figs. 2, 3 and 8, there is formed upon and carried by the magazine 20 at the under side thereof to the rear of but adjacent to the plunger 21, a plurality of perforating members 38, in this instance shown in the form of a segment, these being positioned to coöperate with the recesses 37 formed in the anvil 33, so that when the magazine is positioned downwardly upon the anvil, a portion of the ma-

terial upon the blade will be perforated so that when the staple is properly clenched therethrough such portion of the box or material will not be entirely detached, but will be in a ready position to be detached when the portion carrying the staple is pulled to open the box or receptacle.

In the form of anvil shown in Fig. 7, the carrying member 25^a is provided with an enlarged end 39 which has a flat forward edge 75 and carries the clenching recess 40, this being especially adapted for use in connection with articles, portions of which do not have to be punctured by the blades as heretofore described and particularly relates to securing box corners and the like.

A small blade 32^a of hard tempered metal provided with a piercing anvil 33^a and a clenching recess 34^a is carried by the block 25^a so that this block combines the ordinary anvil and piercing anvil in one.

It will thus be seen that in both forms of anvils, the manipulating and adjusting screw 29 is in ready access to the operator from the front so that the parts may be readily moved to present either one of the recesses 34, 36, 34^a or 40 below and in line with the staple severing and delivering plunger 21. By this means, this form of machine may be adapted for various uses 95 and by attaching the machine for operating by foot power both hands of the operator are free to position the work upon the various anvils to receive the staples.

From the foregoing description, it is evident that by the peculiar mounting of the lever 6 and its spring 16, the magazine and its spring elevated plunger, that upon the depression of the lever 6 and during the depression thereof, the magazine is first lowered and brought to rest upon the anvil, the plunger not being depressed to drive and clench the staple until the above is accomplished. This is of the utmost importance in a machine of this character in that a sharp blow is necessary to properly drive and clench the staple and the anvil and magazine must be in the closest proximity to each other at this time.

What is claimed is:

1. A staple affixing machine, including a base, a staple magazine having a delivering plunger carried thereby, a laterally swinging anvil mounted upon the base and provided with a plurality of staple clenching means for registration one at a time with the plunger of the magazine, and manually operable anvil releasing and locking means connected to the anvil and mounted in the base.

2. A staple affixing machine, including a base, a staple magazine having a delivering plunger carried thereby, a laterally swinging anvil mounted upon the base and provided with a plurality of staple clenching

means for registration one at a time with the plunger of the magazine, and manually operable anvil releasing and locking means connected to the anvil and mounted in the 5 base, said latter means, including a manually operable screw connected to and projecting from the anvil and provided with a head for engaging the under side of the base.

3. A staple affixing machine, including a 10 base, a support carried thereby, an operating lever pivoted in the support for movement to and from the base, a spring connected to the support and to the lever for holding the lever elevated, a staple magazine connected 15 to the base, a delivering plunger mounted in the magazine and having a spring for normally holding the plunger elevated, means for connecting the upper end of the plunger to the operating lever whereby the spring 20 thereof assists in elevating the lever, an anvil carried by the base and disposed to be below the plunger, two rods connected to the lever intermediate of the ends thereof, and means connected to both rods for operating 25 the lever and plunger in opposition to the springs.

4. A staple affixing machine, including a base, a standard carried thereby, an operating lever pivoted in the standard for movement to and from the base, a spring connected to the standard and to the lever for holding the lever elevated, a staple magazine connected to the base, a delivering plunger mounted in the magazine and having a spring for normally holding the plunger elevated, means for slidably connecting the upper end of the plunger to the operating lever, an anvil carried by the base and disposed to be below the plunger when the 30 magazine is at rest upon the anvil, the spring of the plunger being disposed to assist in relieving the weight of the lever from the first spring, a treadle, two rods connected to the lever and depending from each side 35 thereof, and a treadle carried connection adjustably connected to the two rods.

5. A staple affixing machine, including a base, a standard projecting upwardly from one end thereof, an arm carried by the support, an operating lever pivoted to the support and projecting above the base, a spring connected to the arm and exerting pressure upon the under side of the lever to elevate the lever, a pin rotatably mounted in the lever intermediate of its ends, two rods connected to the pin and projecting downwardly, an anvil mounted upon the base at the end remote from the standard, a staple magazine pivoted to the base with its free end so arranged as to be movable toward and from the anvil, a spring elevated plunger carried by the magazine, means for connecting the upper end thereof to the free end of the lever, whereby the spring of the plunger augments the first spring in elevating 60

the lever, and a foot treadle connected to the two rods for depressing the lever, magazine and plunger in succession.

6. A staple affixing machine, including a base, a staple magazine having a staple delivering plunger carried by the base, an anvil having a plurality of clenching means, a pin connecting the anvil for lateral swinging movement relatively to the base, said base adjacent the anvil being provided with an arcuate slot concentric to the pin, and a set screw projecting through the arcuate slot and engaging the anvil, the arrangement being such that the anvil is released, adjusted and locked to present one clenching means at a time to the plunger.

7. A staple affixing machine, including a base, an anvil mounted upon the base and having staple clenching means, a standard carried by the base at the end remote from the anvil, a staple magazine mounted upon the base for movements to and from the anvil, a spring elevated staple driving plunger mounted in the magazine, a lever fulcrumed in the standard and connected at its free end to the upper end of the plunger, a spring for elevating the lever engaging the lever between its fulcrum and the connection thereof, two rods connected to the lever, and means connected to both rods for depressing the lever and through the lever, the magazine and plunger.

8. A staple affixing machine, including a base, an anvil mounted upon the base and having a staple clenching means, a standard carried by the base, a lug carried by the standard, a staple magazine mounted upon the base for movement to and from the anvil, a staple driving plunger mounted in the magazine, a lever fulcrumed in the standard and connected to the plunger, a spring supported by the lug and engaging the lever to elevate the lever and through the plunger the magazine, and manually operated means for operating the lever in opposition to the spring.

9. A staple affixing machine, including a base, an anvil mounted upon the base and having a staple clenching means, a standard carried by the base, a lug carried by the standard, a staple magazine mounted upon the base for movement to and from the anvil, a staple driving plunger mounted in the magazine, a lever fulcrumed in the standard and connected to the plunger, a spring supported by the lug and engaging the lever to elevate the lever and through the plunger the magazine, a plurality of rods adjustably connected together and to the lever, and a foot treadle connected to the rods for depressing the lever in opposition to the spring.

10. A staple affixing machine, including a base, a staple magazine having a staple delivering plunger carried by the base, an an-

vil having a plurality of clenching means, a pin connecting the anvil for lateral swinging movement relatively to the base, said base adjacent the anvil being provided with an arcuate slot concentric to the pin, a set screw projecting through the arcuate slot and engaging the anvil, the arrangement being such that the anvil is released, adjusted and locked to present one clenching means at a time to the plunger, and coöperable means carried by the magazine and the anvil, one portion of such means being adjacent to the anvil abutting face of the magazine while the other portion is adjacent the clenching means of the anvil, whereby as a staple is driven and clenched through the work, such work is perforated adjacent the staple.

11. A staple affixing machine, including a

base, an anvil having a clenching means, a staple magazine having a staple delivering plunger carried by the base, and coöperable means carried by the magazine and the anvil, one portion of such means being adjacent the anvil abutting face of the magazine 25 while the other portion is adjacent the clenching means of the anvil, whereby as a staple is driven and clenched through the work, such work is perforated adjacent the staple. 30

In testimony whereof we affix our signatures in presence of two witnesses.
